CLAIM

The ornamental design for a mast for a robot, as shown and described.

DESCRIPTION

FIG. 1 is a mast for a robot in a perspective view;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines are included for the purpose of illustrating portions of the mast for a robot that form no part of the claimed design.
